CIGARETTE CASE

Harvey G. Kittredge and Frank W. Williams,
Dayton, Ohio, assignors to Foilfilm, Inc., Dayton, Ohio, a corporation of Ohio

Application February 23, 1935, Serial No. 7,792

4 Claims. (Cl. 229—87)

Our invention relates to a new article of manufacture for use as a cigarette package.

It is the object of our invention to provide a cigarette package that is impervious to moisture and can be folded and sealed.

It is a further object to provide a cigarette package which has a transparent window so that the condition of the package can be observed.

It is our object to provide a structurally weak, 10 metallic foil reinforced with a transparent metal-adhering material that becomes plastic and adhesive under the application of slight pressure and heat. Such a material in a cigarette package makes it possible to eliminate multiple operations in the formation of a package and makes it possible to eliminate the paper wrapping on the inside of tin foil, which is characteristic of the present day cigarette package.

It is our object to provide a single sheet of 20 material of reinforced tin foil and a further object of providing such a sheet in which certain areas have no tin foil so as to provide transparent windows through the backing material for the tin foil that is thus left uncovered.

Referring to the drawing, Figure 1 is a vertical section through a package having one end open and one end sealed, showing the composite structural arrangement of the walls and the package. This section is taken on the line 1—1 of Figure 2.

Figure 2 is an end elevation of the package 30 from the sealed end.

Figure 3 is a section on the line 3—3 of Figure 4. It shows the modification with a transparent window on the side walls of the package.

Figure 4 is an end elevation of the sealed end of the package of Figure 3.

Figure 5 is a side elevation of the package of Figure 3.

Referring to the drawing in detail, the package is formed of a structurally weak tin foil designated 1 to which is integrally joined a metal-adhering, synthetic resin material 2. This material is tough, metal-adherent, substantially transparent and has a smooth surface that is non-adherent to any object under ordinary conditions of temperature and pressure.

Upon heat being applied to the tin foil or its structurally strong backing, this backing becomes adhesive, and upon the ends of the package being folded as indicated, this material will adhere to the adjacent metal surface and to itself, forming a tight hermetical seal that keeps the moisture and flavor in the tobacco of the cigarettes.

The metal foil runs in thickness from .0001 to

.025 inch. The foil may be made of any of the standard metals for this purpose.

The structurally strong supporting backing for the metal may be made of a variety of synthetic resinous materials provided they have the characteristics in the compound of metal-adherence, transparency, a hard, smooth, tough body at ordinary temperatures, and the capacity for becoming adhesive upon the application of slight heat and slight pressure.

A typical compound which we have found satisfactory is the following:

We have found that among the materials that provide for a tough body film are cellulose acetate, cellulose nitrate, vinyl acetate, vinyl acetate 15 polymerized, vinyl acetate modified with acetaldehyde, and various other equivalent resins that are normally flexible and hard and tough, but not adherent to metal.

We have found that substances that are adherent to metal, but which are not flexible, hard and tough are such materials as a saturated alkyd resin, coumeron-indene resin, a phenolic resin shellac, dewaxed shellac, and gum dammar.

We have found that materials which are suitable plasticizers are chlorinated diphenyl, triphenyl phosphate, tricresyl phosphate and dibutyl phthalate. Such plasticizers are flexible and control the drying rate.

We find such solvents as toluol and naphtha 30 to be suitable for purposes of this invention.

We find that the addition of linoleate of lead controls the drying rate, and the addition of waxes and stearates controls the tendency of the compound in films to stick to one another, particularly where it is necessary to roll the composite foil film, after having been produced in the interim, before it is utilized in commerce.

Our invention consists of the combination of a tough body means and adherent means, and a 40 flexible means, such as a polymerizer, together with a suitable solvent. The result is a non-hygroscopic metal and glass adherent film that can be used for the production of strong metal foil products, labels, cigarette packages and other 45 forms of containers.

2.4 grams of vinyl acetate, 6 grams of phenolic resin, 2.5 grams of chlorinated diphenyl and 18 cc. of toluol, when applied at 105 degrees C. for 50 three minutes to metal foil, provide a strong, tough product having a water-white brilliancy and sparkle. The product is strongly adherent to metal and cannot be detached therefrom at room temperatures, and the metal can be at- 55

tached to glass by the application of heat and slight pressure.

There are a variety of other combinations than indicated but we have found the foregoing to be 5 a satisfactory one in practice.

The package is provided with a sealed end as indicated in the several figures of the drawing and it will be noted that this backing for the tin foil, when the folding has taken place at the end 10 of the package, will form a tight seal due to its metal adherent qualities when slightly heated. This is indicated at the sealing surfaces marked 3 and 4.

Referring to Figures 3, 4 and 5, this backing 15 film is left without any foil facing as at 5. As the backing film is substantially transparent and is tough, strong and durable and has a smooth surface, this provides a window through which the cigarettes can be viewed, while at either end there is the metal foil cap suitably sealed. The 20 ends are sealed with the combined metal and backing reinforcement while the intermediate side walls are transparent. This backing material is light and flexible so that the total weight 25 of the package is materially reduced from that of the customary package now known in the art.

One of the outstanding features of this package is that the synthetic resin compound is non-hygrosopic. There is nothing to absorb moisture as in the case of cellulose or natural resin. It is disastrous to a cigarette package to associate 30 with it moisture-absorbing materials. That is the reason for the use of tin foil and that is the disadvantage of the paper backing of tin foil. The further disadvantage is that with the present 35 day package there is no means of sealing the package against the entrance of moisture or against the loss of moisture from the tobacco.

It will be understood that we desire to comprehend within our invention such modifications as may be necessary to adapt it to varying conditions and uses.

Having thus fully described our invention,

what we claim as new and desire to secure by Letters Patent, is:

1. A new article of manufacture for use as a moistureproof package consisting of a non-hygrosopic transparent, flexible film adherent to 5 metal under the application of heat, having uncovered areas and areas covered by metal foil integrated therewith whereby a package can be formed having transparent portions and metal foil covered portions. 10

2. A new article of manufacture comprising a relatively strong non-hygrosopic transparent film that becomes adhesive under heat and that is metal adherent, and end coatings of metallic foil integrated therewith whereby a window is 15 left between the metallic foil ends for the observation of the contents of the package and whereby upon folding, the ends of the film may be thermoplastically united with itself and adjacent areas of foil to form a moistureproof end 20 seal for the package.

3. A moistureproof package comprising an inner transparent wrapper of thermoplastic non-hygrosopic metal adherent synthetic resin having integrally secured to the outside thereof 25 structurally weak metal foil extending to the ends of the inner wrapper, the ends of said package being folded and sealed by thermoplastically uniting areas of said inner wrapper with adjacent areas of said metal foil. 30

4. A moistureproof package comprising an inner transparent wrapper of thermoplastic non-hygrosopic metal adherent synthetic resin having integrally secured to the outside thereof areas of structurally weak metal foil separated to provide a window and extending substantially to the end of the inner wrapper, the ends of said package being folded and sealed by thermoplastically uniting areas of said inner wrapper with adjacent areas of said metal foil. 40
